UNITED STATES PATENT OFFICE.

OLIVER ARNOLD, OF WORCESTER, MASSACHUSETTS, ASSIGNOR TO THE T. K. EARLE MANUFACTURING COMPANY, OF SAME PLACE.

MACHINE FOR FEEDING WIRE.

SPECIFICATION forming part of Letters Patent No. 315,882, dated April 14, 1885.

Application filed January 30, 1885. (No model.)

To all whom it may concern:

Be it known that I, OLIVER ARNOLD, a citizen of the United States, residing at Worcester, in the county of Worcester and State of Massachusetts, have invented certain new and useful Improvements in Wire-Feeding Mechanism; and I declare the following to be a description of my said invention, sufficiently full, clear, and exact to enable others skilled in the art to which it appertains to make and use the same, reference being had to the accompanying drawings, which form a part of this specification.

The object of my present invention is to produce a more perfect and desirable apparatus for automatically feeding wire intermittently to a given distance, as in machines for setting card-teeth and for other purposes, and to afford facilities for the accurate adjustment of the feed-movement; also, to provide a yielding connection between the movable block and operating-lever, so that the block may have positive stops, while said lever may be actuated positively in both directions by its driving-cam. These objects I attain by the mechanism constructed as shown and described, the particular features of improvement claimed being hereinafter definitely specified.

In the drawings, Figure 1 is a plan view of a wire-feeding mechanism embracing my improvements. Fig. 2 is a part side view, part section, at line *x* *x*, showing the mechanism. Fig. 3 is an end view of the guide-frame. Fig. 4 shows the back of the jaw-pressure spring.

In reference to parts, A indicates the frame of the machine. B indicates the stationary jaw-block, and C the movable block or head through which the wire W passes. Said blocks B and C are respectively provided with grip pins or jaws *b* *b'* and *c* *c'* for holding the wire at proper intervals of action. The pins *b* and *c* are adjustable, but are rigidly held at working position by binding-screws *a*, while the jaws or pins *b* and *c* are free to move in and out in the action of the mechanism, springs *s* being provided, if desired, for forcing them outward or away from the wire W when released by the pressers.

D indicates an adjustable stop or screw set

in the end plate, A', for gaging the backward movement of the block C.

C² indicates a stud or bunter fixed in the forward end of the block C to act as a stop for the forward movement against the block B, which latter is rigid upon the frame A. The block C works back and forth on the guide E between the limit of the stops C² and D. The lever F, by which the block C is moved, is fulcrumed at *f*, and is operated by the grooved cam G being positively actuated in both directions. Through the end of the lever F is a transversely-located stud, *m*, one end of which rests against the raised portion of the block C, while the other end rests against a flatspring or yielding plate, H, fixed on the lever F, as indicated. The manner of connecting the lever with the block is a feature of my invention. A spring, C³, is arranged in connection with the block C and lever F for pressing said lever forward and maintaining proper relation between said parts.

I indicates a spring-plate secured at its end *i* to the frame, and located parallel with the guide E at such distance from the block as will accommodate the jaw grip-pin *c*, so that the latter will, by said spring-plate I, be forced inward firmly against the wire W when the plate I is at normal position. A lever-head, J, is hinged to the end of the spring I, one end of which head is in position to act on the grip-pin *b*, while the other is connected with a slide-rod, K, that is operated by a cam, L, on the drive-shaft M, as illustrated. The operation of the cam L drawing back the rod K swings the end of the head J against the grip-pin *b*, closing *b* *b'*, so as to hold the wire in the block B, and at the same time by the leverage of said head J overcomes the spring of the plate I and lifts it from the grip-pin *c*, thus opening *c* *c'* and releasing the wire in the block C. Thus, while one grip or jaw is closed the other is opened, and vice versa. The cam G is made to operate the lever F in both directions and to give to said lever a greater movement or throw than is required for the feed-block C, the action of which is limited by the stop devices D and C². The block C and wire W are consequently positively brought up fully at

each end of the movement, and the action can be adjusted to a very fine degree of accuracy in the feeding of the wire. The excess of movement or overthrow of the lever F on its forward stroke is relieved by the yielding of the spring H back of stud m, and on the backward stroke by the yielding of the spring C³.

In the operation the method of feeding forward the wire is substantially similar to the method commonly heretofore employed—viz., the jaws b b' grip and hold the wire while the block C moves backward, and the jaws c c' grip and hold the wire, carrying it forward with the forward movement of said block, one 15 pair of jaws being closed on the wire when the other is relieved, as will be readily understood.

Mechanism for feeding wire is quite common in which a stationary block having grip devices and a reciprocating block having grip 20 devices and operated by a swinging lever and cam are employed. It will therefore be understood that I do not herein make claim, broadly, to such features, my invention comprising the improved constructions and arrangements 25 specified, illustrated, and defined.

What I claim as of my invention, and desire to secure by patent, is—

1. The combination, in a wire-feeding mechanism, of the block C, with stops for limiting 30 its movement in both directions, the operating-lever F, attached to said block by a yield-

ing connection, and the actuating-cam G, adapted for positively imparting motion to said lever in both directions and in excess of the movement of the feed-block, as hereinbefore set forth. 35

2. The combination, with the movable jaw-block C, in a wire-feeding device, of the operating-lever F, provided with the spring H, the stud m, the stops D and C³, and the spring 40 C³, substantially as shown and described.

3. The combination, with the grip pins or jaws b and c, of the spring-plate I, attached to the frame at i, the lever-head J, hinged to said spring-plate, the rod K, and cam L, as shown 45 and described.

4. In combination, as shown, the stationary jaw-block B, having grip-pins b b', the movable jaw-block C, having grip-pins c c', the guide-rod E, the lever F, having the spring H and 50 stud m, the spring C³, the adjustable stop D, the spring-plate I, with lever-head J, the connection-rod K, the grooved lever-operating cam G, and rod-operating cam L on shaft M, said parts constructed as herein described. 55

Witness my hand this 21st day of January, A. D. 1885.

OLIVER ARNOLD.
